United States Patent Office

Des. 196,403
Patented Sept. 24, 1963

196,403

OUTBOARD MOTOR, OR SIMILAR ARTICLE

James R. Thomas, 2203 S. Millwood, Wichita, Kans.

Filed Aug. 4, 1961, Ser. No. 66,204

Term of patent 7 years

(Cl. D71—1)

FIG. 1

FIG. 2

FIG. 1 is a front perspective view of an outboard motor, or similar article, embodying my new design.

FIG. 2 is a rear perspective view thereof.

I claim:

The ornamental design for an outboard motor, or similar article, as shown.
